MACHINE FOR THE ROTARY SHEARING OF
METAL OR THE LIKEGerald M. Hambleton, Sr., and Robert G.
Heinrich, Rochester, N. Y.

Application March 29, 1947, Serial No. 738,122

14 Claims. (Cl. 164—61)

1

This invention relates to the rotary shearing of metal or the like and more particularly to a machine for shearing sheet metal stock of either coil or sheet form.

In the manufacture of sheet metal of either the ferrous or non-ferrous type, the rolling mills utilize machines which shear or slit the sheet stock into a number of strips. All of these machines, however, are designed to handle a definite sheet width and are usually catalogued as an 18, 24, or 36 inch machine. While an 18 inch sheet could be sheared or slit on a 24 inch machine, a 24 inch sheet could not be sheared or slit on an 18 inch machine. This is due to the arrangement of the bearing for the arbors which carry the cutters. The bearings are usually carried in an integral block for both the upper and lower arbors or in separate blocks which are locked together when the arbors and cutters are in the shearing position. These machines are also of such a size that the ordinary small machine shop cannot afford to install such a machine, and, as a result, must resort to the use of a vertical single stroke type of metal shearer.

In a great many instances, a manufacturer orders sheet metal in 18, 24, or 36 inch widths and then finds that these sheets must be slit or sheared to some smaller width for punch press parts, etc. While small length sheets may be sheared by a vertical shearer, the time necessary for shearing a large number of sheets is both costly and time consuming. To this end, the arrangement of the various elements of our invention solves the above shortcomings and at the same time permits the manufacture of a machine of relatively small cost.

The primary object of the invention is to provide a machine for the shearing and/or slitting of sheet metal stock in which any width and length of sheet may be sheared.

A further object of the invention is to provide a machine for the shearing and/or slitting of sheet metal in which the bearings for the upper and lower arbors upon which the cutters are mounted are independent of each other.

Another object of the invention is to provide a machine for the shearing and/or slitting of sheet metal in which the bearings for one end of the upper and lower arbors are separated to provide an unobstructed passageway for the metal being sheared.

And yet another object of the invention is to provide a machine for the shearing of metal in which the bearing members for one end of the arbors can be easily removed for replacement of the cutters and easily and accurately returned to their original positions.

A still further object of the invention is to provide a machine for the shearing of sheet metal in which the upper arbor is adjustable with respect to the lower arbor.

2

And still a further object of the invention is to provide a machine for the shearing of sheet metal in which a pair of rolls are mounted near the arbors and cutters for flattening the metal and removing the burr, if any, after passing through the cutters.

A further object of the invention is to provide a machine for the shearing of sheet metal which is relatively simple in construction, easy to operate, and relatively inexpensive to manufacture.

These and other objects of the invention will be apparent from the description which follows:

The objects of the invention are embodied in a machine for the rotary shearing of sheet or coiled sheet metal comprising a bed plate having a vertical upright section in which one end of an arbor on which cutters are mounted is journaled. The other end of the arbor is journaled in a removable and adjustable bearing member mounted on the bed plate. One end of the upper arbor which is vertically aligned with the lower arbor is journaled in a vertical extension of a horizontal member which is secured to the vertical section on the bed plate. The other end of the upper arbor is journaled in a bearing plate which is pivotally located on the horizontal member. A motor through a variable speed gear box drives the lower arbor, and the upper arbor is connected thereto by an endless chain for driving the arbors in opposite directions. A set of rolls are mounted in spaced relation to the arbors for flattening the burrs on the metal after it has been sheared.

Reference is now made to the accompanying drawings wherein similar reference characters designate similar parts and wherein:

Fig. 1 is a front elevation of the machine embodying the invention;

Fig. 2 is a plan view of the machine;

Fig. 3 is a side elevation of the machine with the flattening rolls removed for clarity;

Fig. 4 is a side elevation of the flattening rolls;

Fig. 5 is a diagrammatic view showing a possible arrangement of the cutters and spacers on the upper and lower arbors;

Fig. 6 is a view taken substantially on the line 6—6 of Fig. 1;

Fig. 7 is a view taken substantially on the line 7—7 of Fig. 2;

Fig. 8 is a view taken substantially on the line 8—8 of Fig. 4;

Fig. 9 is a view taken substantially on the line 9—9 of Fig. 4; and

Fig. 10 is a view taken substantially on the line 10—10 of Fig. 1.

In the illustrated embodiment of the invention, the bedplate 1 is provided with the extensions 2 and lugs 3 for securing the bedplate 1 by means of the bolts 4 to the top 5 of the mounting frame 6. A motor 7 is mounted on the cross plate 8. The bed plate 1 has integral therewith or secured

thereto a vertical section 9, the purpose of which will be described hereinafter. The bedplate 1 is provided with a slot 10 and grooves 11 for the bearing member 12 which is provided with tongues 13 for engaging the grooves 11. The bearing member 12 is slideable and adjustable in the grooves 11 and locked in position by means of the bolt 14. The bearing member 12 has journalled therein the one end 15 of the lower arbor 16 which has its other end 17 journalled in the vertical section 9 and the plate 18.

The upper arbor 19 which is vertically aligned with the arbor 16 and spaced therefrom is mounted in the horizontal bearing member, designated broadly by the numeral 20, which comprises the horizontal section 21 which is substantially parallel to the bedplate 1 and a vertical portion 22 which has a tongue portion 23 for engaging the cut-out portion 24 in the vertical section 9 and is secured in position by the bolts 25 and the locating pins 26. The end 27 of the arbor 19 is mounted in the sleeve 28 carried in the block 29 which is adjustably mounted in the bearing plate 30 by means of the adjusting screw 31. The bearing plate is milled out, as indicated by the numeral 32, and is provided with a slot 33 which is engaged by the tongues 34 on the block 29, see Fig. 10.

The locating means for the bearing plate 30 comprises the dowel pins 35 which are fixed to the horizontal section 21 and which are accurately located for mounting the plate 30 in proper spaced relation to the bearing member 12 to provide a free passageway, indicated by the numeral 36, for the metal being sheared.

For the purpose of removing the cutters 37 and the spacers 50 from the arbor 19, as will be more fully described hereinafter, the plate 30 is maintained in its supporting position by the hinge plates 38. The hinge plates 38 are secured to the bearing plate 30 by means of the bolts 39 or by welding thereto and are provided with slots 40 through which the bolts 41 extend to secure the plate 30 in position.

The bearing means for the end 45 of the arbor 19 is similar to that for the end 27. The tongue portion 23 of the vertical section 22 is milled out, as indicated at 32 in Fig. 1, and provided with a slot 46 for the extensions 47 on the block 48. The block 48 is provided with a sleeve 49 through which the end 45 of the arbor 19 passes. With this arrangement for mounting the arbor 19, all the parts associated therewith can be assembled as a unit for mounting on the vertical section 9.

The cutters 37, as shown in Fig. 5, are mounted on the arbors 16 and 19 with spacers 50 therebetween and clamped in position by the collars 51 which are turned on the threaded portions 52 of the arbors 16 and 19. As shown in Figs. 1, 2, and 3, a guide plate 53 is mounted on the vertical section 9 and the posts 54 for guiding the sheet metal into the rotating cutters 37. The plate 53 is provided with guide members 55 which are adjustable by means of the bolt 56 along the slot 57. This provides a fixed guideway for the operator to direct the sheets of metal to be sheared into the cutters 37. When sheets are to be sheared that are wider than the length of the arbors 16 and 19, the outer guide is removed and the sheet will then pass between the bearing plate 30 and the bearing member 12. With this open-end arrangement for supporting the ends 15 and 27 of the arbors 16 and 19, respectively, the cutters 37 can be mounted on the arbors for first

shearing a number of excessively wide sheets of metal or the like to a suitable width, or multiple width of the desired size, for easier handling, and then rearranging the cutters 37 to shear the narrow width sheets into the still narrower desired widths. Since the method of shearing sheet metal by the use of rotary cutters is well-known to those skilled in the art, it is not deemed necessary to enter into any discussion of the actual theory of the shearing action aside from the fact that the cutters 37 on both the arbors 16 and 19 are adjusted so they are tangent to a common line, see Fig. 5.

The above described arrangement for the end 15 bearings of the arbors 16 and 19 also lends itself to quick removal and remounting of the cutters 37. By simply loosening the bolt 14, the bearing member 12 can be slid off the bed plate 1 with the end 15 of the arbor 16 fully exposed for removing or replacing the cutters 37. In a like manner, by releasing the bolts 41, the bearing plate 30 may be pulled forward off the locating dowels 35 and then swung about the bolts 41, as indicated in Fig. 3, to a position of rest on the horizontal section 21, thereby exposing the end of the arbor 19 for removing or replacing the cutters 37. When the plate 30 is returned to its bearing position the dowels 35 assure proper locating of the plate 30 with respect to the bearing member 12.

Inasmuch as the cutters 37 must be reground periodically to maintain good shearing action, their diameter is usually decreased by several thousands of an inch as a result of the regrinding. To provide for this variation in cutter diameters, the arbor 19 is adjusted with respect to the arbor 16 by means of the screws 31 which are secured to the blocks 29 and 48 for raising or lowering the blocks in the slots 33 and 46, respectively.

Coming now to the drive means for the arbors 40 16 and 19, the motor 7 which may be of the multiple or variable speed type has fixed to its shaft 60 a sprocket 61. The end 17 of the arbor 16 has keyed thereto, adjacent the plate 18, a sprocket 62. An endless chain member 63 encircles the sprockets 61 and 62 to drive the arbor 16 directly from the motor 7, see Fig. 1. The end 45 of the arbor 19 also has keyed thereto a sprocket 64 which is driven by a second endless chain member 65 which also encircles the idler sprockets 66 and 67 and the sprocket 73 on the end 17 of the arbor 16 between the plate 18 and the vertical section 9 to drive the arbors in opposite directions. The idler sprocket 67 is mounted between the plate 18 and the vertical section 9 on the shaft 68 which is journalled in the plates 69 and 70. The plate 69 is adjustably mounted on the vertical section 9 while the plate 70 is adjustably mounted on the bearing plate 18 by means of the bolts 71 engaging the slots 72. With this arrangement for mounting the sprocket 67, any difference in the center distance between the arbors 16 and 19 due to variation in cutter diameter, which will cause a slack in the chain member 65, can be readily adjusted for by changing the horizontal position of the sprocket 67.

When sheet metal is sheared by means of rotary cutters, the metal after being sheared sometimes has a burr and is not flat sideways. To correct this condition a pair of burring rolls 75 and 76 are mounted on the bed plate 1 beyond the arbors 16 and 19. The lower roll 75 has a reduced portion 77 and a bearing sleeve 78 and is journalled in the bearing member 79 secured to the bed plate 1 by the bolts 80. The other reduced portion 81 of the roll 75 also carries a

sleeve 78 and is journalled in the extension 83 of the vertical section 9. The reduced portion 81 extends beyond the extension 83 and is also journalled in a supplementary bearing member 84 for the sprocket 85 which is keyed to the portion 81. An endless chain member 86 encircles the sprocket 85 and a third sprocket 87 mounted on the end 17 of the arbor 16 to drive the roll 75.

The upper roll 76 is also provided with reduced portions 90 and 91. The portion 90 has a bearing sleeve 92 and is journalled in the block 93, see Fig. 7. The block 93 is provided with grooves 94 for engaging the tongues 95 in the U-shaped member 96, see Fig. 6. The block 93 rests on the coil spring 97 and is held in position by the plate 98 secured to the member 96 by the screws 100. The block 96 is held in position on the bearing member 79 by the latches 101 which are secured in position by the bolts 102, see Fig. 4.

The portion 91 of the roll 76 also carries a bearing sleeve 92 and is journalled in the block member 103. The block 103 is pivotally mounted between the supporting members 104 by the pins 105. The members 104 are provided with grooves 106 for slidably engaging the tongues 107 on the extension 83, and are supported on the extension 83 by the springs 108. A plate 109 is provided with an arcuate cut-out 110 and tends to maintain the members 104 in position. The adjusting screw 111 in the plate 98 and the adjusting screws 112 in the plate 109 maintain the block 93 and the members 104, respectively, in proper position so that the rolls 75 and 76 are in proper intimate contact. By adjusting the screws 111 and 112, the pressure with which the roll 76 contacts the roll 75, and hence the metal being sheared, may be varied.

It will be noted from Fig. 2 that the rolls 75 and 76 are approximately the same length as the arbors 16 and 19. When wide sheets are being sheared, the bolts 102 are released, the latches 101 removed from engagement with the bolts 102 and the upper roll 76 swung upward and into the arcuate cut-out portion 110 in the plate 109. The roll 76 then carries with it the U-shaped member 96, the block 93, the spring 97 and the plate 98, and no obstruction then remains in the way of the sheet being sheared. The roll 75 now acts as a support for the sheared sheet.

Since other modifications of the construction shown are possible, the scope of the invention is not to be limited to the illustrated embodiment but is defined by the appended claims.

We claim:

1. In a machine for the rotary shearing of metal or the like, the combination comprising a bed plate for said machine having a vertical upright section thereon, bearing means mounted on said bed plate, an arbor journalled in said vertical section and said bearing means for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a second bearing means mounted in the vertical portion of said support member for one end of said second arbor, a third bearing means for the other end of said second arbor mounted on said horizontal section and spaced from said bearing means to permit the metal being sheared to pass therebetween, and means connecting said first and second arbors for driving said arbors in opposite directions.

2. In a machine for the rotary shearing of metal or the like, the combination comprising a bed plate for said machine having a vertical upright section thereon, a bearing member mounted on said bed plate, an arbor journalled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a bearing means mounted in the vertical portion of said support member for one end of said second arbor, a bearing plate for the other end of said second arbor mounted on said horizontal section and spaced from said bearing member to permit the metal being sheared to pass therebetween, means on the horizontal portion of said support member for locating said bearing plate, and means connecting said first and second arbors for driving said arbors in opposite directions.

3. In a machine for the rotary shearing of metal or the like, the combination comprising a bed plate for said machine having a vertical upright section thereon, a bearing member mounted on said bed plate, an arbor journalled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a support plate mounted on said horizontal section and spaced from said bearing member to permit the metal being sheared to pass therebetween, bearing means mounted in the vertical portion of said support member and in said support plate mounting said second arbor in spaced relation with respect to said first arbor, means on the horizontal portion of said support member locating said support plate in a predetermined position, and means connecting said first and second arbors for driving said arbors in opposite directions.

4. In a machine for the rotary shearing of metal or the like, the combination comprising a bed plate for said machine having a vertical upright section thereon, a bearing member mounted on said bed plate, an arbor journalled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a support plate mounted on said horizontal section and spaced from said bearing member to permit the metal being sheared to pass therebetween, bearing means adjustably mounted in the vertical portion of said support member and in said support plate mounting said second arbor in spaced relation with respect to said first arbor, means on the horizontal portion of said support member locating said support plate in a predetermined position, and means connecting said first and second arbors for driving said arbors in opposite directions.

5. In a machine for the rotary shearing of metal or the like, the combination comprising a bed plate for said machine having a vertical up-

right section thereon, an adjustable bearing member mounted on said bed plate, an arbor journaled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a support plate mounted on said horizontal section and spaced from said bearing member to permit the metal being sheared to pass therebetween, bearing means mounted in the vertical portion of said support member and in said support plate mounting said second arbor in spaced relation with respect to said first arbor, means on the horizontal portion of said support member locating said support plate in a predetermined position, means carried by said support member and said support plate for vertically adjusting the bearing means of said second arbor, and means connecting said first and second arbors for driving said arbors in opposite directions.

6. In a machine for the rotary shearing of metal or the like, the combination comprising a bed plate for said machine having a vertical upright section thereon, a bearing member mounted on said bed plate, an arbor journaled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a support plate mounted on said horizontal section and spaced from said bearing member to permit the metal being sheared to pass therebetween, bearing means mounted in the vertical portion of said support member and in said support plate mounting said second arbor in spaced relation with respect to said first arbor, means on the horizontal portion of said support member locating said support plate in a predetermined position, means carried by said bearing plate retaining said bearing plate in a hinged relationship with said horizontal portion, and means connecting said first and second arbors for driving said arbors in opposite directions.

7. In a machine for the rotary shearing of metal or the like, the combination comprising a bed plate for said machine having a vertical upright section thereon, a bearing member mounted on said bed plate, an arbor journaled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a bearing plate for the other end of said second arbor located on said horizontal section in spaced relation from said bearing member to permit the metal being sheared to pass therebetween, locating means on the horizontal portion of said support member for said bearing plate, means carried by said bearing plate and pivotally connected to said horizontal portion retaining said bearing plate on said locating means during the shearing of said metal and retaining said bearing plate in a hinged relation with said horizontal portion dur-

ing the withdrawal of said bearing plate from said locating means for the removal of said cutters from said second arbor, and means connecting said first and second arbors for driving said arbors in opposite directions.

5 8. In a machine for the rotary shearing of metal or the like, a vertical upright section thereon, a bearing member mounted on said bed plate, an arbor journaled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a support plate mounted on said horizontal section and spaced from said bearing member to permit the metal being sheared to pass therebetween, bearing means adjustably mounted in the vertical portion of said support member and in said support plate mounting said second arbor in spaced relation with respect to said first arbor, locating dowels secured to the horizontal portion of said support member locating said support plate in a predetermined position, means carried by said support member and said support plate for vertically adjusting the bearing means of said second arbor, and means connecting said first and second arbors for driving said arbors in opposite directions.

20 9. In a machine for the rotary shearing of metal or the like, the combination comprising a bed plate for said machine having a vertical upright section thereon, a bearing member mounted on said bed plate, an arbor journaled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a support plate mounted on said horizontal section and spaced from said bearing member to permit the metal being sheared to pass therebetween, bearing means adjustably mounted in the vertical portion of said support member and in said support plate mounting said second arbor in spaced relation with respect to said first arbor, locating dowels secured to the horizontal portion of said support member locating said support plate in a predetermined position, means including adjusting screws in said support member and said support plate and connected to said bearing means for said second arbor for adjusting said second arbor with respect to said first arbor, and means connecting said first and second arbors for driving said arbors in opposite directions.

25 10. In a machine for the rotary shearing of metal or the like, the combination comprising a bed plate for said machine having a vertical upright section thereon, a bearing member mounted on said bed plate, an arbor journaled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a support plate mounted on said horizontal section and spaced from said bearing member to permit the metal being

sheared to pass therebetween, bearing means mounted in the vertical portion of said support member and in said support plate mounting said second arbor in spaced relation with respect to said first arbor, means on the horizontal portion of said support member locating said support plate in a predetermined position, horizontally extending members having longitudinal slots therein retaining said bearing plate on said locating means during the shearing of said metal and retaining said bearing plate in a hinged relation with said horizontal portion during the withdrawal of said bearing plate from said locating means for the removal of said cutters from said second arbor, and means connecting said first and second arbors for driving said arbors in opposite directions.

11. In a machine for the rotary shearing of metal or the like, the combination comprising a bed plate for said machine having a vertical upright section thereon, a bearing member adjustably mounted on said bed plate, an arbor journalled in said vertical section and said bearing member for mounting a set of cutters thereon, a second arbor vertically aligned with said first arbor for mounting a second set of cutters thereon, a support member having a vertical portion detachably mounted on said vertical section and a horizontal portion extending from said vertical portion parallel to said bed plate, a support plate mounted on said horizontal section and spaced from said bearing member to permit the metal being sheared to pass therebetween, bearing means mounted in the vertical portion of said support member and in said support plate mounting said second arbor in spaced relation with respect to said first arbor, locating dowels secured to the horizontal portion of said support member locating said support plate in a predetermined position, means including adjusting screws in said support member and said support plate and connected to said bearing means for said second arbor for vertically adjusting said second arbor with respect to said first arbor, horizontally extending members having longitudinal slots therein retaining said bearing plate on said locating dowels during the shearing of said metal and retaining said bearing plate in a hinged relation with said horizontal portion during the withdrawal of said bearing plate from said locating dowels for the removal of said cutters from the second arbor, and means connecting said first and second arbors for driving said arbors in opposite directions.

12. In a machine for the rotary shearing of metal or the like, the combination comprising a bed plate for said machine having a vertical upright section thereon, a bearing member adjustably mounted on said bed plate, an arbor journalled in said vertical section and said bearing member for mounting a set of cutters for said metal thereon, a second arbor spaced from said first arbor and vertically aligned therewith for mounting a second set of cutters thereon, a horizontal bearing member for said second arbor detachably mounted on said vertical section and extending therefrom parallel to said bed plate and spaced from said first mentioned bearing member to permit the metal being sheared to pass therebetween, a variable speed driving means connected to said first arbor, a sprocket on said first arbor, an idler sprocket mounted on

said vertical section, a second idler sprocket mounted on said vertical section, a sprocket on said second arbor, and an endless drive member encircling said sprockets for driving said arbors and cutters in opposite directions.

13. In a machine for the rotary shearing of metal or the like, the combination comprising a bed plate for said machine having a vertical upright section thereon, a bearing member adjustably mounted on said bed plate, an arbor journalled in said vertical section and said bearing member for mounting a set of cutters for said metal thereon, a second arbor spaced from said first arbor and vertically aligned therewith for mounting a second set of cutters thereon, a horizontal bearing member for said second arbor detachably mounted on said vertical section and extending therefrom parallel to said bed plate and spaced from said first mentioned bearing member to permit the metal being sheared to pass therebetween, a variable speed driving means connected to said first arbor, a sprocket on said first arbor, an idler sprocket mounted on said vertical section, a second idler sprocket mounted on said vertical section and horizontally adjustable with respect to said other sprockets to compensate for changes in said cutters, a sprocket on said second arbor, and an endless drive member encircling said sprockets for driving said arbors and cutters in opposite directions.

14. In a machine for the rotary shearing of metal or the like, the combination comprising a bed plate for said machine having a vertical upright section thereon, a bearing member adjustably mounted on said bed plate, an arbor journalled in said vertical section and said bearing member for mounting a set of cutters for said metal thereon, a second arbor spaced from said first arbor and vertically aligned therewith for mounting a second set of cutters thereon, a horizontal bearing member for said second arbor detachably mounted on said vertical section and extending therefrom parallel to said bed plate and spaced from said first mentioned bearing member to permit the metal being sheared to pass therebetween, a sprocket on said first arbor, a variable speed motor having a sprocket thereon, an endless chain member encircling said sprockets for driving said first arbor, a second sprocket on said first arbor, an idler sprocket mounted on said vertical section, a sprocket on said second arbor, a second idler sprocket mounted on said vertical section and horizontally adjustable with respect to said other sprockets to compensate for changes in said cutters, and an endless drive member encircling the second sprocket on said first arbor, said idler sprockets, and the sprocket on said second arbor for driving said arbors and cutters in opposite directions.
